(57) **CLAIM**

The ornamental design for an inflatable watercraft, as shown and described.

DESCRIPTION

FIG. 1 is a front perspective view of an inflatable watercraft showing my new design;

FIG. 2 is a front view of the design shown in FIG. 1;

FIG. 3 is a rear view of the design shown in FIG. 1;

FIG. 4 is a right side view of the design shown in FIG. 1;

FIG. 5 is a top view of the design shown in FIG. 1; and,

FIG. 6 is a bottom view of the design shown in FIG. 1.

The dashed lines in the drawings depict portions of the inflatable watercraft that form no part of the claimed design. The dot-dash lines in the drawings depict environmental subject matter and form no part of the claimed design.
